Swank, Inc., a corporation of Delaware

Application March 20, 1946, Serial No. 127,691

Term of patent 14 years

(Cl. D64—12)

To all whom it may concern:

Be it known that I, Viola T. Howard, a citizen of the United States of America, residing at Saylesville, county of Providence, State of Rhode Island, have invented a new, original, and ornamental Design for an Alphabet for Forming Monograms or Similar Article, of which the following is a specification, reference being had to the accompanying drawing, forming a part thereof.

Fig. 1 is a face view of the letters of the alphabet showing my design;

Fig. 2 is a side view of one of the letters, "A" being a typical example; and

Fig. 3 is a face view of a spacer for insertion between two letters.

I claim:

The ornamental design for an alphabet for forming monograms or similar article, substantially as shown.

VIOLA T. HOWARD.
